FOLDING ANCHOR BREAKING DEVICE

Henry R. Weeks, Coronado, Calif.

Application July 6, 1938, Serial No. 217,714

6 Claims. (Cl. 114—208)

(Granted under the act of March 3, 1883, as
amended April 30, 1928; 370 O. G. 757)

This invention relates to a folding anchor breaking or releasing device, and has for an object to provide means for easily breaking a folding anchor so that it may be folded up and put away in storage to occupy a minimum amount of space.

Reference is had to the anchor disclosed in United States Patent 2,075,827 of April 6, 1937, which shows a folding anchor of the type for which this invention is generally intended, although it is equally applicable to any other folding anchor wherein the cross-arms and fluke arms are held in operative position by means of spring tongues on one of the arms cooperating with detents or recesses on the other of the arms.

In folding anchors of this general type which are especially intended for use in seaplane service or in like watercraft service, one defect has been apparent, that is, it is difficult to "break" for folding it, especially when the operator may be standing on a skimpy platform on the side of a flying boat hull. A screwdriver or other lever-like implement is often used for this purpose, but there is extreme difficulty in performing the operation satisfactorily as well as the possibility of losing the implement overboard.

It is an object of this invention to provide a breaking or releasing device taking the place of the screwdriver or other lever-like implement, which performs the breaking or releasing operation much more easily and readily, and yet cannot be lost, inasmuch as this breaking device is a permanent attachment of the anchor, out of the way when the breaking device is not being operated, yet instantly available for service whenever needed for this particular purpose.

With the foregoing and other objects in view, the invention consists in the construction, combination and arrangement of parts hereinafter described and illustrated in the drawing, in which,

Fig. 1 is an elevational view of a folding anchor to which this invention has been applied;

Fig. 2 is a sectional view on line 2—2 of Fig. 1, and

Fig. 3 is a sectional view on line 3—3 of Fig. 2.

There is shown at 10 the folding anchor to which this invention has been applied and comprises the shank 11, U-shaped in cross section, at one end of which is a cable attaching shackle 12. At the other end of the shank 11 are hinged the fluke arms 13 by means of bolts and nuts 14, which bolts and nuts 14 also serve as securing means for the U beams 15 to which are pivoted U-shaped brackets 16 by bolts and nuts 22 car-

rying the cross-arms 17 which are U-shaped in cross section. The U-shaped brackets 16 have their bights extending across the open space of the cross-arms 17 and are shaped as shown in dotted outlines in Fig. 2, being cut away to provide T-shaped spring tabs 18 which end in enlarged heads 19 having curved lips 29. The spring tabs 18 extend through reduced recesses 20 in the shank 11, the heads 19 being too large to pass through the reduced recesses 20, but are small enough to pass through the enlarged recesses 21. As long as the spring head 19 is in the reduced recess 20 the cross-arms 17 are held locked in operative position against pivoting about the bolts and nuts 22. The sides of the brackets 16 are provided with extending tongues 23, while the ends of the fluke arms 13 are provided with suitably placed apertures 24, through which the tongues 23 extend, thus holding the fluke arms 13 locked against pivoting about bolts 16.

To release or break the anchor for folding, it is necessary for the spring heads 19 to be depressed until the spring tabs 18 leave the reduced recesses 20 and the spring head 19 is in a position to pass through the enlarged recess 21 in the shank 11, thus allowing the cross-arms 17 to be pivoted against the shank 11. When both cross-arms have thus been pivoted, both fluke arms 13 are released for pivoting, due to the withdrawal of the tongues 23 from the apertures 24.

This invention is intended to facilitate the depression of the spring head 19 to the position to pass through the enlarged recess 21. Slidably pivoted on one of the bolts 14 is a lever 25 provided at one end with a clip 26 for securing it in inoperative position to the side of one of the fluke arms 13. On the other side of the bolt 14 the lever 25 is provided with a foot 27 terminating in a cam 28. The length of the foot 27 from its pivoting bolt 14 is such that rotation of the lever 25 about such bolt 14 causes the cam 28 to contact the top of the spring head 19 and depress it at least as far as the enlarged recess 21, thus permitting one of the fluke arms 17 to be folded about its pivoting bolt 22. The lever 25 is then slid on its pivoting bolt 14 to the other side of the fluke arm 13 and the operation is repeated, bringing cam 28 into operation against the spring head 19 of the other cross-arm 17, thereby releasing such other cross-arm 17 for pivoting against the shank 11, which, as it withdraws its tongues 23 from the fluke arms 13, finally releases both fluke arms 13 for

pivoting toward the shank 11, leaving the anchor in folded-up position.

When it is desired to place the anchor in operative position again, the fluke arms 13 are unfolded to a straight angle with each other and then the cross-arms 17 are likewise unfolded to a straight angle position with each other, the curved lips 29 raising the spring head 19 through the enlarged recess 21 until the spring tabs 18 5 may enter into the reduced recesses 20 to thus lock the fluke arms and cross-arm in operative position. The breaking or releasing lever 25 is a permanent part of the anchor, and being held in inoperative position by the clip 26, and does 10 not interfere with the normal operation of the anchor, yet is instantly available when the anchor has been raised preparatory to being folded and stowed away.

Other modifications and changes in the portions and arrangements of the parts may be 20 made by those skilled in the art without departing from the nature of the invention, within the scope of what is hereinafter claimed.

The invention described herein may be manufactured and used by or for the Government 25 of the United States of America for governmental purposes without the payment of any royalties thereon or therefor.

Having thus set forth and disclosed the nature 30 of this invention, what is claimed is:

1. For use with a folding anchor of the type having arms pivoted to the shank and having a spring member with an enlarged head on one of said arms adapted to extend through a reduced 35 recess for holding said arm in operative anchor position, an anchor breaking device comprising a lever pivoted to said shank and a cam member extending from said lever adapted to depress the spring to release the spring head from the reduced recess when the lever is rotated about its 40 pivot.

2. For use with a folding anchor of the type having arms pivoted to the shank and having a spring member with an enlarged head on one of 45 said arms adapted to extend through a reduced recess for holding said arm in operative anchor position, an anchor breaking device comprising a lever pivoted to said shank, a cam member extending from said lever adapted to depress the spring from the reduced recess when the lever is 50 rotated about its pivot, and a clip member

formed on the other end of said lever adapted to cooperate with one of said cross-arms for holding said lever in inoperative position.

3. For use with a folding anchor of the type having arms pivoted to the shank and having a 5 spring member with an enlarged head on one of said arms adapted to extend through a reduced recess for holding said arm in operative anchor position, an anchor breaking device comprising a lever pivoted to said shank, a cam member extending from said lever adapted to depress the spring from the reduced recess when the lever is rotated about its pivot, and a clip member formed on the other end of said lever adapted to cooperate with one of said cross-arms for holding said lever in inoperative position by the clip 10 member 15 for said lever on the shank being one of the pivot bolts for one of the anchor arms, said lever being slidable on such pivot bolt to place said cam in spring-releasing position at either side thereof. 20

4. In combination with a folding anchor having pivoted arms held in anchor position by a T spring having its head extended into a recess in the anchor shank, a breaking device comprising a lever fixedly fulcrumed on one of the arms 25 pivots and a cam on said lever adapted to depress said T spring head out of its recess when said lever is rotated to thereby break the folding anchor.

5. In combination with a folding anchor having pivoted arms held in anchor position by a T spring having its head extended into a recess in the anchor shank, a breaking device comprising a lever fixedly fulcrumed on one of the arms pivots and a cam on said lever adapted to depress said T spring head out of its recess when 30 said lever is rotated to thereby break the folding anchor and means on said lever to cooperate with one of said anchor arms to hold said lever in inoperative position.

6. A breaking device for a folding anchor, said anchor having pivoted arms held from folding by a spring, said breaking device being pivoted on one end of said breaking device adapted to release the spring when said breaking device is pivoted, and means on the other end of the breaking device for releasably holding the breaking device in position convenient for use. 45
